US0D1068440S

(12) **United States Design Patent** (10) **Patent No.:** **US D1,068,440 S**
(45) **Date of Patent:** **** Apr. 1, 2025**

(54) **DOOR LOCK-DOWN DEVICE**

(71) Applicant: **Scott W. Levandowski**, Glendale, AZ (US)

(72) Inventor: **Scott W. Levandowski**, Glendale, AZ (US)

(**) Term: **15 Years**

(21) Appl. No.: **29/964,389**

(22) Filed: **Sep. 23, 2024**

(51) LOC (15) Cl. **08-09**

(52) U.S. Cl. **USPC D8/402**

(57) **CLAIM**

The ornamental design for a door lock-down device as shown and described.

DESCRIPTION

FIG. 1 is a isometric view of a door lock-down device showing the new design;

FIG. 2 is a rear view thereof;

FIG. 3 is a front view thereof;

FIG. 4 is a left-side view thereof;

FIG. 5 is a right-side view thereof;

FIG. 6 is a top view thereof; and,

FIG. 7 is a bottom view thereof.

1 Claim, 6 Drawing Sheets
